UNITED STATES PATENT OFFICE.

JACOB WEINTZ, OF CLEVELAND, OHIO, ASSIGNOR TO THE STRONG, CARLISLE & HAMMOND COMPANY, OF CLEVELAND, OHIO, A CORPORATION OF OHIO.

ELECTRIC FURNACE.

Application filed January 26, 1927. Serial No. 163,704.

This invention relates to furnaces and particularly to so-called electric furnaces such as are commercially employed industrially in heat treating metallic articles.

5 Furnaces of the type to which reference has been made comprise principally a chamber lined with refractory material around the sides of which are spaced a number of heating elements adapted to be brought to incandescence by the passage of electric current therethrough, these elements being also spaced from the refractory lining which becomes heated in use also to incandescence and thus radiates and distributes the heat 15 generated in the incandescent heating element.

It is the object of my invention to provide a surface conformation of this refractory lining which will take the utmost advantage 20 of the incandescence of heating elements in receiving heat radiated therefrom toward the furnace walls, and return the same between the elements to the articles placed in the furnace for treatment.

25 The exact nature of the invention together with advantages arising therefrom will be obvious from the following description taken in connection with the drawings in which Fig. 1 is a typical horizontal section through 30 such a furnace in which my invention has been incorporated; Fig. 2 is a vertical section through the same, as along line 2—2, Fig. 1; and Fig. 3 is an enlarged detail showing the manner in which the heat is distributed by my construction.

35 Referring now to the drawings the furnace is generally of the usual and well known construction comprising a heating chamber 1 immediately formed by a rectangular box 40 of a very high grade of refractory material 2. This refractory material is backed by a layer of fire brick 3 insulated by a layer of asbestos 4 from a thick covering of heat insulating material 5 contained within a metallic outer covering 6. The refractory material 2 thus forms in fact a lining for the heating chamber of the furnace, access being had to this chamber through an opening 7. Spaced as indicated in Fig. 1 along the side 45 and rear walls of the furnace are a number of vertically extending heating pencils or elements 8, preferably of circular section, each positioned between a pair of contactors 9 by which an electric circuit may be directed 50 through the several heating elements to

bring the same into incandescence, all in a well known manner.

When the heating elements are brought into an incandescent state it is evident that articles resting upon the usual tray 10 within the furnace will be heated to a considerable extent by direct radiation therefrom. A large portion of the heat generated by the elements however, passes to the refractory lining to bring the same also into incandescence, and is re-radiated therefrom, between the elements to the articles.

60 While every unit of a radiating surface may in fact radiate in all directions therefrom yet such radiation has been found in 70 practice to apparently conform somewhat to the laws of light transmission; the return angle of a secondary radiating surface such as the refracting lining 2 herein, bearing the same relation to the angle of incidence as 75 would a light ray originating in one of the heating elements herein pass to the lining and be refracted therefrom.

In order to take full advantage of this 80 fact I form that portion of the material 2 immediate to each of the heating elements 8 of parabolic section as indicated in Figs. 1 and 3, the focus of each parabola being the center of its corresponding heating element.

85 In order that the heating elements be spaced as closely as possible and, therefore, that a larger number of elements may be employed on a wall, the parabolic sections are not greatly extended, that is, only a relatively short portion, that of greatest curvature, is 90 employed. In fact, such portion as is employed approximates in section very closely a circular arc. With such an arrangement the heating elements in order that they may be located at the foci are spaced somewhat 95 from the general plane of the wall, and in fact in a plane spaced somewhat forward of the plane in which the sides of the depressions meet each other, the side portions of adjacent depressions joining each other from 100 ridges parallel with the heating elements and having gradually sloping sides.

105 The nature of the result of this arrangement is illustrated diagrammatically in Fig. 3. Heat is radiated generally directly toward the center or contents of the furnace from each of the incandescent heating elements as along the radial broken lines from the front or inner faces of the elements. The opposite or rear faces of the elements how- 110

- ever, radiate only toward the lining 2. The lines of heat transmission are radial in this case also, but owing to the parabolic surface conformation of the lining provided, this 5 heat is returned or re-radiated along lines substantially perpendicular to the general surface of the lining, that is upon the rectangular system by the light full lines in Fig. 3. At the inner corner of the heating chamber the parabolic curvature of the lining has 10 been modified as indicated at 11 according to the same system whereby the lines of most efficient radiation are from that portion of the lining towards the center of the furnace. 15 The result of my invention is a greater temperature in the working part of the furnace than has heretofore been accomplished with the same size of elements, and a more uniform distribution of heat in this area. 20 What I claim is:
1. In a furnace having a wall, a refractory lining therefor having parallel depressions of curved section the side portions of which meet at an angle to form ridges, and parallel
- heating elements spaced forwardly of the 25 plane of said ridges and one before each of said depressions.
2. In a furnace having a wall, a refractory lining therefor having shallow parallel depressions of parabolic section the side portions of which meet at an angle to form ridges, and heating elements located one along the focal line of each depression and spaced forwardly of the plane of said ridges. 30
3. In a furnace having a pair of walls arranged in angularly disposed planes to meet along a line, refractory linings for said walls having depressions parallel with said line and of curved section, adjoining side portions of adjacent depressions, one of each wall, 35 meeting along a line substantially farther removed from the line of meeting of said walls, than the general plane of the face of either lining is removed from the face of the corresponding wall. 40
- In testimony whereof I hereby affix my signature.

JACOB WEINTZ.
